(57) CLAIM

The ornamental design for an air chamber manifold, as shown and described.

DESCRIPTION

FIG. 1 is a perspective view of the air chamber manifold showing my new design;

FIG. 2 is a right plan side view of the air chamber manifold of FIG. 1;

FIG. 3 is a left plan side view of the air chamber manifold of FIG. 1;

FIG. 4 is a front plan view of the air chamber manifold of FIG. 1; and,

FIG. 5 is a top plan view of the air chamber manifold of FIG. 1.

The broken line shows the environment and is for illustrative purposes only and forms no part of the claim to design.
